US00D433005S

United States Patent [19]

McGugan

[11] Patent Number: Des. 433,005

[45] Date of Patent: ** Oct. 31, 2000

[54] **HEADSET COMPATIBLE WIRELESS TRANSCEIVER**

[75] Inventor: **Steve McGugan**, Klampenborg, Denmark

[73] Assignee: **GN Netcom A/S**, Ballerup, Denmark

[**] Term: **14 Years**

[21] Appl. No.: **29/092,258**

[22] Filed: **Aug. 14, 1998**

[30] **Foreign Application Priority Data**

Feb. 23, 1998 [DK] Denmark ..... MA 1998 00221

[51] LOC (7) Cl. **14-03**

[52] U.S. Cl. **D14/155**; D14/142

[58] **Field of Search** D14/137, 138, D14/140, 142, 148, 149, 155, 159, 205, 206, 217-218, 223, 224, 229, 240; 181/129, 130, 135; 379/430, 433, 434, 440; 455/90

[57] **CLAIM**

The ornamental design for a headset compatible wireless transceiver, as shown.

DESCRIPTION

FIG. 1 is a front and top left perspective view showing my new invention;

FIG. 2 is a rear and top right perspective view showing my new invention;

FIG. 3 is a rear and top right perspective view of the stationary unit, shown separately for clarity of illustration;

FIG. 4 is a front elevation view of FIG. 3;

FIG. 5 is a rear elevation view of FIG. 3;

FIG. 6 is a right side elevation view of FIG. 3;

FIG. 7 is a left side elevation view of FIG. 3;

FIG. 8 is a top plane view of FIG. 3;

FIG. 9 is a bottom plane view of FIG. 3;

FIG. 10 is a front and top right perspective view of the portable unit, shown separately for clarity of illustration;

FIG. 11 is a front elevation view of FIG. 10;

FIG. 12 is a rear elevation view of FIG. 10;

FIG. 13 is a right side elevation view of FIG. 10;

FIG. 14 is a left side elevation view of FIG. 10;

FIG. 15 is a top plane view of FIG. 10; and,

FIG. 16 is a bottom plane view of FIG. 10.
